VELOCIPED SADDLE

Harry Golden, New York, N.Y., assignor to Ideas For
Auto and Bike Specialties, Inc., New York, N.Y., a
corporation of New York

Filed July 31, 1967, Ser. No. 8,067

Term of patent 14 years

(Cl. D90—16)

FIG. 1

FIG. 2

FIG. 3

FIGURE 1 is a front perspective view of a velocipede saddle, embodying my new design;

FIGURE 2 is an enlarged sectional view thereof taken substantially along the line 2—2 of FIGURE 1; and

FIGURE 3 is a rear perspective view thereof.

I claim:

The ornamental design for a velocipede saddle, as shown.
